INVENTOR

Henry L. Charles.

BY *Shaw and Charles*
ATTORNEY

UNITED STATES PATENT OFFICE.

HENRY L. CHARLES, OF NEW YORK, N. Y.

ORE-SMELTING FURNACE.

1,394,473.

Specification of Letters Patent.

Patented Oct. 18, 1921.

Application filed January 23, 1920. Serial No. 353,395.

To all whom it may concern:

Be it known that I, HENRY L. CHARLES, a citizen of the United States, residing at New York city, in the county of New York and State of New York, have invented certain new and useful Improvements in Ore-Smelting Furnaces, of which the following is a specification, reference being had therein to the accompanying drawing.

10 My invention relates to improvements in smelting furnaces and has particular reference to means in combination therewith for water jacketing ore inlets thereof, and is in the nature of a continuation in part of my 15 forfeited application No. 200,614.

In the accompanying drawings I have illustrated in Figure 1 partly in cross-section and parts broken away, one side of the upper part of a reverberatory smelting furnace showing an embodiment of my invention. Fig. 2 is a cross-section on the line 2—2 of Fig. 1. Fig. 3 is a view looking down upon the water box structure, shown in Fig. 1. Fig. 4 is an enlarged longitudinal 25 section of the water jacketed ore inlet nozzle. 4 indicates one of the side walls of the furnace, and 5—6 the arch roof thereof which it will be observed is cut away to receive the water box 7 which is also cut away 30 in the center providing a passage 8 into which the water jacketed ore inlet 9 projects the same being pivotally mounted at 10 by any suitable means such as the ball and socket joint shown. 11 indicates the nozzle 35 through which the ore passes from the supply pipe 12 and is suitably water jacketed as shown to better advantage in Fig. 4, wherein it will be observed that 13—13' indicate the water inlets and outlets, the ore 40 passing down through the central passage 14 into the furnace.

15 indicates a hollow slide provided with water inlets and outlets 16—17 and a tapered cut-away portion 18 in the center to allow 45 for the passage of the nozzle 11. This slide is mounted beneath the flange 19 upon the top of the water box and over the inlet opening 8, the water in the outside water box traversing the chamber 20 around said opening 8 and having inlets and outlets 21—22

as shown. The box is preferably seated upon the lower arch 6 which is cut away to provide an opening corresponding with the area of the lower portion of the opening 8, and the box passes through the upper part 55 of the arch as shown, so as to enable the same to be applied and removed with facility. With an arrangement of this kind it will be readily observed that the ore can be discharged adjacent the side wall or thrown 60 into the interior of the furnace simply by shifting the nozzle 11 as indicated in dotted outline in Fig. 1, while at the same time the ore inlet is thoroughly protected from the heat of the furnace by the water jacketing illustrated and for this purpose any suitable connection to the water main and waste pipe may be made as may be found desirable.

Of course it will be understood that various modifications may be made in the construction and arrangement of parts without departing from the spirit of the invention as claimed.

I claim:

1. In combination with a furnace of the class described and the ore inlet therefor, of a water box surrounding said ore inlet and a water jacket around said ore inlet nozzle. 75

2. In combination with the water box surrounding an ore inlet for a furnace of the class described, a water jacketed slide cover therefor. 80

3. In combination with the water jacketed ore inlet of a furnace such as described, means for pivotally mounting the nozzle of said ore inlet. 85

4. In a furnace of the class described, an ore inlet and a nozzle therefor pivoted to swing at an angle thereto. 90

5. In combination with a furnace of the class described, an ore inlet and a water box therefor, said ore inlet pivotally mounted and said water box cut away radially from 95 the pivotal mounting of said ore inlet.

In testimony whereof I hereunto affix my signature.

HENRY L. CHARLES.
